UNITED STATES PATENT OFFICE.

HIRAM Q. HOOD, OF WEBB CITY, MISSOURI.

SPIKE-PULLER.

SPECIFICATION forming part of Letters Patent No. 784,679, dated March 14, 1905.

Application filed October 10, 1904. Serial No. 227,912.

To all whom it may concern:

Be it known that I, HIRAM Q. HOOD, a citizen of the United States, residing at Webb City, in the county of Jasper and State of Missouri, have invented certain new and useful Improvements in Spike-Pullers; and I do declare the following to be a full, clear, and exact description of the invention, such as will enable others skilled in the art to which it appertains to make and use the same.

My invention relates to improvements in spike-pullers adapted for use in pulling spikes from railway-ties; and it consists in the construction, combination, and arrangement of devices hereinafter described and claimed.

This invention is an improvement on the spike-puller described and claimed in my co-pending application for Letters Patent of the United States filed April 7, 1904, Serial No. 202,075, allowed June 30, 1904, the object of my present invention being to effect improvements in the construction of the operating-lever.

In the accompanying drawings, Figure 1 is a front elevation of my improved spike-puller, showing the same in operative position. Fig. 2 is a side elevation of the same, showing the rail on which the puller is mounted in section; and Fig. 3 is a detail perspective view of the inner portion of the lever and the heel-plates thereof, the latter being shown detached from the lever.

The lever of my improved spike-puller comprises a bar 1 and a pair of heel-plates 2, which are detachably secured to the lower end thereof on opposite sides of said bar. Each of said heel-plates comprises a web portion 3 and a curved arm 4 at the rear and lower side thereof, the front ends of the said curved arms projecting beyond the front sides of the said webs or plates, as at 5, and being provided with alined transverse openings 6. The said curved arms of the heel-plates are adapted to bear on the tread of the rail and to form the fulcrum for the lever, and the said heel-plates are provided on their opposing inner sides with parallel flanges 7, which form recesses between them to receive opposite sides of the lower portion of the bar. The said heel-plates and

the bar are provided with alined transverse 50 openings, through which extends a bolt 8, which serves to clamp the heel-plates to the lever-bar and detachably secure the heel-plates thereto, so that they may be readily removed therefrom for repairs or to be replaced in 55 the event that either or both of the said heel-plates become broken or damaged.

It will be observed by reference to the drawings that the web, flanges, and curved arms of each heel-plate are formed integrally, that the arrangement of the curved arms on the outer, rear, and lower sides of the webs is such as to greatly strengthen the heel-plates, and that the arrangement of the parallel flanges on the inner sides of the webs is also such as to greatly 65 strengthen the construction of the heel-plates.

A swivel member 9 is disposed pivotally between the projecting ends or lugs 5 of the heel-plates and is provided with trunnions 11 at its ends, which have their bearings in the openings 6, with which said ends or lugs are provided. A bit 12, which has an opening 13 to clear the head and jaws 14 to engage the opposite sides of the head of a spike, is provided with a screw-threaded stem 15, which passes through an unthreaded transverse opening with which the swivel member is provided. On the said screw-threaded stem and engaging the same is a nut 16, which serves to adjust the bit with reference to the swivel member 70 75 80 according to the work to be performed by the puller.

Having thus described my invention, what I claim as new, and desire to secure by Letters Patent, is—

1. In a spike-puller, a lever comprising a bar, heel-plates detachably secured to opposite sides thereof, each comprising an integral web and a curved arm, said plates having flanges on their opposing sides bearing on opposite 90 sides of the lever-bar, and said curved arms having projecting portions forming lugs, in combination with a swivel member having its bearings in said lugs, and a bit connected to said swivel member.

2. In a spike-puller, a lever comprising a lever-bar, heel-plates on opposite sides thereof having flanges in their opposing sides bear-

85

95

ing on opposite sides of the lever-bar, said heel-plates being further provided with curved arms projecting beyond the front sides of the heel-plates and forming lugs, and a bolt passed through alined openings in the heel-plates and the lever-bar and detachably clamping them together, in combination with a swivel member having bearings in the said lugs, a bit having a stem adjustably connected to the swivel mem-

ber, and an adjusting-nut on the said stem, to substantially as described.

In testimony whereof I have hereunto set my hand in presence of two subscribing witnesses.

HIRAM Q. HOOD.
